UNITED STATES PATENT OFFICE.

RALPH V. SAGE, OF WESTMONT, PENNSYLVANIA.

EXTENSIBLE CAR-STAKE.

No. 833,975.

Specification of Letters Patent.

Patented Oct. 23, 1906.

Application filed August 27, 1906; Serial No. 382,110.

To all whom it may concern:

Be it known that I, RALPH V. SAGE, a citizen of the United States, residing in the borough of Westmont, in the county of Cambria and State of Pennsylvania, have invented 5 certain new and useful Improvements in Extensible Car-Stakes; and I do hereby declare the following to be a full, clear, and exact description of the invention, such as will enable others skilled in the art to which it appertains to make and use the same.

My invention consists of various novel and useful improvements in side stakes for cars, with particular reference to what is known 15 as "gondola cars;" and certain of the objects of my invention are to provide an economical and practical form of extensible stake which will act both as a side stake for stiffening and strengthening the permanent sides of 20 the car and which also has an extensible portion that may be projected above the car sides to retain light or bulky lading—such as lumber, bark, structural material, or any other kind of goods which extend above the 25 sides of the car.

One of the particular objects of my invention is to provide a side stake of the character described which will be a permanent part of the car and which cannot be removed therefrom, thus being always in condition for use 30 when required. This feature of my invention is a particular and important one, for the reason that heretofore when a load on a car was higher than the permanent sides 35 thereof and the lading of such a nature that it became necessary to confine it laterally in order to prevent it from falling from the car it was the practice to retain said lading in position by inserting temporary wooden stakes 40 in the stake-pockets, which latter are provided on the sides of some cars for that purpose. These temporary stakes extended above the sides of the car and were generally tied across their tops by nailing boards to the upper ends 45 of the opposite stakes or by securing strands of wire or other flexible material thereto. These temporary wooden stakes were not furnished with the car and were no permanent part of same, and after their temporary use was finished they were usually removed during the process of unloading, and as it is not ordinarily known when the car 50 will be again loaded with similar material these temporary stakes were either thrown away or diverted to other uses, thus making it necessary to go to the trouble and expense 55

of providing new temporary stakes for each high lading.

Although my invention may be applied to various kinds of cars, both of wood and metal, I will for the purpose of simplifying the specification and illustration confine this description to its application to a metal gondola car.

My invention in general consists of a hollow stake or envelop of trough-shaped section, with integral flanges projecting therefrom, which may be made of pressed or rolled metal secured to the car side by rivets or bolts passing through the flanges aforesaid, 60 and I prefer to arrange my hollow stake in such location that the side thereof can be secured to one of the cross-transoms of the car, thereby tying the framework together and forming a more substantial support for the 65 car side. As it is customary in most cases to provide the upper edge of a metal gondola car side with an outwardly-projecting angle secured thereto, I in this case arrange my car-stake on the inside of the car side, thereby 70 allowing the extension portion of same to be projected upward when desired without interference with the projecting angle aforesaid. This arrangement is also useful in that it puts the stake out of the way of being 75 battered, bent, or broken by being forcibly knocked against other cars or obstructions during the movement of the car, this being known to railroad men as "side-swiping."

Inside of the hollow trough-shaped stake or 80 envelop aforesaid I arrange an extension-stake composed of an I-beam or similar section, which latter can be adjusted to any height desired within its limits, said extension portion being provided with means to 85 prevent its loss by neglect, accident, or theft.

When not in use, the extension portion of 90 my stake is lowered within the envelop and its top is preferably below or flush with the top of the car side, thus preventing obstruction with the ordinary lading or injury to the extension-stake itself, as will be readily understood.

My exterior stake of trough-shaped section serves a double purpose, in that it stiffens and maintains the car side in position 100 and at the same time retains the extension portion both in its lowered and in its extended locations.

The top of the extension portion of my 105 stake is furnished with a cleat or rounded button, around the shank of which rope or

wire may be wound, extending from one stake to its companion stake on the opposite side of the car to assist in holding same and the lading in position, and said button also 5 serves as a convenient handhold for pulling said stake upward when required.

Having thus given a general description of my invention, I will now, in order to make the matter more clear, refer to the annexed 10 sheet of drawings, which forms part of this specification and in which like letters and characters refer to like parts.

Figure 1 is a top plan view of a portion of a metal gondola car, showing the sides of the 15 car, the underframing, and my stake arranged at intervals along the inside of the car sides. Fig. 2 is a transverse vertical sectional elevation taken on a plane indicated by the line II II of Fig. 1. Fig. 3 is a longitudinal sectional elevation, on an enlarged scale, taken on the line III III of Figs. 2 and 20 4, showing the lower part of the envelop and the extension-stake and the preferred manner of arranging and connecting same with 25 relation to the car side and underframing. Fig. 4 is a partial sectional plan taken on the line IV IV of Fig. 3, showing the envelop portion and the extension-stake in section and the manner in which the envelop portion 30 is secured to the car side and the car-underframing. Fig. 5 is a longitudinal sectional elevation, on an enlarged scale, somewhat similar to Fig. 3, but showing an alternative form of the lower portion of the envelop and 35 the manner of connecting same to the car side and the underframing, in this case the lower portion of one of the projecting flanges of the envelop being cut away, as shown. The arrangement of my stake shown in Fig. 40 5 is particularly applicable to old cars, as my stake can be attached to same, as shown, without disturbing the connection of the existing transom to the car side. Fig. 6 is a longitudinal vertical sectional elevation, 45 taken on the line VI VI of Fig. 2, showing the upper portion of my trough-shaped stake or envelop and the lower part of the extension-stake mounted therein when the latter is in its closed position. This figure also 50 shows the arrangement of the means for maintaining the extensible stake at the various heights, which in this case consists of a bolt passing through registering holes in the envelop and the extension portion of the 55 stake. Fig. 6 also shows a stop for limiting the upward movement of the extension portion of the stake, thereby preventing its entire withdrawal, as hereinbefore referred to.

Referring now to the various characters of 60 reference on the drawings, 1 is the exterior portion or the envelop of my car-stake, to which is secured the car side 15 by means of the rivets 13 and 14 passing through said car side and holes 7 in the flanges 3 of the envelop portion.

8 is the extension portion of my stake, which is shown as of I-beam section inserted within the envelop and capable of being moved down so as to be practically inclosed therein or to be extended to a considerable 70 height above the top of said envelop, as desired.

The sides 2 2 of the end portion are provided with holes 6 6, and the extension portion of the stake is provided with similar 75 holes 9 9, which may be caused to register with the aforesaid holes 6 6, and the extension-stake 8 may be secured in different positions by inserting the bolt 4 in the registering holes aforesaid, said bolt being temporarily secured in position by means of the cotter 5.

10 is a lug or flat piece of metal secured to the lower portion of the extension-stake to serve as a stop to prevent the complete withdrawal of same, and to assist in this a T-shaped piece of metal 11 is secured to the interior of the envelop, as shown. Upon drawing the extension-stake up to its full height the projection 10 abuts against the inwardly-extending portion of the T-shaped bar 11, which thus stops the extension-stake from being entirely withdrawn, thereby preventing its loss through carelessness or otherwise. 85

Owing to this construction the stake is always ready for use and the expense and delay connected with supplying temporary stakes of wood is eliminated. 90

On the top of my extension-stake 8 I secure a button 12, provided with rounded 100 shank, as shown, which when the stake is in its extended position serves for the attachment of wire, rope, or other flexible material extending from one stake to its companion stake on the opposite side of the car to help 105 in retaining the lading. The rounded top of the button 12 also serves as a convenient handle by which to pull the stake upward when required.

Wire is indicated at 17 in Fig. 2 of the 110 drawings.

The spacing of the holes 6 in the envelop and the holes 9 in the extension-stake is so arranged that the extension portion may be adjusted in height, beginning at one-inch intervals and continuing thereafter at two-inch intervals until the extension portion is withdrawn as far as the stop will permit. The button 12 of the extension-stake is provided with a flange 18, projecting from its lower 115 portion, which holds the stake in its lowered position by resting on the upper surface of the T-shaped bar 11 when said extension-stake is in its lowest location. 120

16 represents the cross-transom of a car, 125 which in this case is shown as of channel-section extending from the center sill to the car side and attached to both of these parts, the attachment to the car side being shown as rivets 14, which also pass through the ex- 130

tending flange of the envelop, as shown in Figs. 1, 2, and 4.

19 indicates a hole or opening in the car-floor to permit my stake to pass through same.

20 is the car-floor secured to the cross-transom, as shown, and it is also secured to the car side by means of its upturned flange 22.

23 represents the flange on the bottom of the car side, represented in this case as integral with the car side.

24 is the top flange of the car side, indicated in this case as a separate angle riveted thereto, while 21 indicates a notch in or the cut-away portion of the lower part of the side flange 3, as shown in the alternate form of construction illustrated in Fig. 5.

It should be especially noted that the trough-shaped envelop with its projecting flanges and the I-beam extension portion are both particularly well adapted to serve the purposes intended in an economical and efficient manner, and I have found by actual design that a stake of this kind can be made of less size than a continuous wooden stake to serve the same purpose. This permits me to apply my stake to the outside of cars without exceeding the allowable limits of the side clearance prescribed by the different railroads, and thus make a wider car of greater capacity than if wooden stakes are used. My improved stake also has the advantage that it is always ready for use when required, thus obviating the expense and delay of supplying and fitting temporary stakes for high lading.

Although I have shown, illustrated, and described my improved stake as attached to the inside of a metal gondola car, I wish it understood that it is equally applicable to the outside of such a car, the only change necessary for this being to turn the top-flange angle at the top side inward, so as not to interfere with the extension-stake, or said top-flange angle may be cut away at or bent around said stake, and I wish it understood that my stake is equally applicable to other cars; but the changes needed for this will be obvious to those skilled in this art. I make the exterior portion or envelop of my car-stake of trough-shaped section open on one side, as this is a particularly-strong form and one that is capable of being rolled of iron or steel or pressed from a single plate or sheet of metal.

Although I have shown and described my improvements in considerable detail, I do not wish to be limited to the exact and specific details shown and described, but may use such substitutions, modifications, or

equivalents thereof as are embraced within the scope of my invention or as pointed out in the claims.

Having thus described my invention, what I claim, and desire to secure by Letters Patent, is—

1. The combination with a metal car of a car-stake comprising a trough-shaped section with integral side flanges projecting therefrom, means for securing same to the car side through the flanges aforesaid, an adjustable metallic stake mounted within the opening of the trough-shaped stake aforesaid and means for securing said adjustable stake in various positions as desired. 75

2. The combination with a metal car of a car-stake comprising a trough-shaped section with integral side flanges projecting therefrom, means for securing said trough-shaped section to the car side through the flanges aforesaid, said trough-shaped section being also secured through one of its sides to the car-transom, an adjustable metallic stake mounted within the opening of the trough-shaped stake aforesaid and means for securing said adjustable stake in various positions as desired. 85

3. The combination with a metal car of a car-stake comprising a trough-shaped section with integral side flanges projecting therefrom, means for securing same to the car side through the said flanges, said car-stake extending downwardly through an opening in the car-floor and being attached through one of its sides to the side of the adjoining car-transom, an adjustable metallic stake mounted within the opening of the trough-shaped stake aforesaid and means for securing said adjustable stake in various positions as desired. 95

4. The combination with a metal car of a car-stake comprising a trough-shaped section with integral side flanges projecting therefrom, means for securing said trough-shaped section to the car side through the flanges aforesaid, said trough-shaped section being also secured through one of its sides to the car-transoms, an adjustable metallic stake mounted within the opening of the trough-shaped stake aforesaid, means for securing said adjustable stake in various positions as desired, and means for preventing the withdrawal of said adjustable stake from its extreme upward and downward positions. 105 110

In testimony whereof I hereto affix my signature in the presence of two witnesses.

RALPH V. SAGE.
